SYSTEM FOR HIGH-FREQUENCY HEATING OF WORK PIECES

Lourens Blok and Gooitzen Zwanenburg, Eindhoven, Netherlands, assignors, by mesne assignments, to North American Philips Company, Inc., New York, N.Y., a corporation of Delaware

Application February 24, 1956, Serial No. 567,576

Claims priority, application Netherlands March 3, 1955

2 Claims. (Cl. 266—4)

The invention relates to a system for high-frequency heating of work pieces. More particularly, the invention relates to a high frequency heating system comprising a time switch to be operated by a starting-contact in order to heat the work piece for a limited period of time and, moreover, cooling means having a switching device for the release of cooling fluid to cool the work piece with a certain time lag relative to the closure of the starting contact. The cooling fluid may constitute, for example, a water jet applied subsequent to the thermal treatment.

The invention has for its object to materially simplify the control of the systems referred to above.

In accordance with the invention, the system is provided with such a coupling between the starting-contact circuit and the cooling switching device that the release or non-release of the cooling fluid depends upon the closure time of the starting contact being shorter or longer than the said time lag.

In order that the invention may be readily carried into effect, it will now be described more fully with reference to the following drawing, wherein:

Fig. 1 is a schematic diagram of one embodiment of the system according to the invention in a perspective view;

Fig. 2 is a schematic diagram of an embodiment of a timing circuit which may be utilized in the system of Fig. 1; and

Fig. 3 is a schematic diagram of an embodiment of a relay circuit which may be utilized in the system of Fig. 1.

The system shown in Fig. 1 is constituted by a high-frequency furnace having a feed-back electron tube oscillator, which is housed in a metal casing 1. The high-frequency furnace is preferably constructed as described in U.S. Patents 2,756,314, issued July 24, 1956 to Blok, and 2,773,192, issued December 4, 1956 to Blok et al.

The front panel of the casing 1 is provided with a plate 2 of insulating material, through which the output conductors 3, 4 of the high-frequency furnace are taken to the outside. To these output conductors 3, 4 is connected a working coil 5. The working coil 5 surrounds a work piece 6 to be heated, which bears on a working table 7, mounted on the front panel.

In order to control the power transferred to the work piece 6 the front panel is provided with a manual control-wheel 8, by which the coupling between the high-frequency oscillator and the load can be varied by mechanical means, as described for example in U.S. Patent 2,662,162, issued December 8, 1956 to Blok.

The side panels of the casing 1 are provided with air slots 9, and the right-hand side panel is provided with a switching arm 10 to switch on the supply device for the high-frequency generator.

Along the top side of the front panel provision is made of a measuring and control board 11, which is movable in order to render the control-apparatus mounted behind it readily accessible for supervision.

A starting contact S is provided on the board 11,

2

which is also provided with a wattmeter 13 to measure the output power.

Behind the board 11 provision is made of a time switch 14, which is connected through a conductor 15 to the connecting terminals of the starting contact S. The time switch 14 serves to switch on the high-frequency heating for a limited period of time. In order to render this period adjustable, the time switch 14 is provided with a time-adjusting mechanism 16, the front side of which projects through a recess in the control-board 11, when it is closed, this front side being thus accessible to the operator.

The time switch 14 may, of course, comprise various types of apparatus, one of which types of apparatus may, for example, comprise a mechanical time switching clock. In the present case use is made of an electronic time switch, the details of which will be explained with reference to Fig. 2.

The device comprises furthermore a cooling switching device 18, to be connected to the water mains through a pipe 17, in order to release a water jet through a pipe 19 provided over the work piece.

For the cooling operation the top surface 20 of the work table 7 is depressed and provided with slots 21, which open into an outlet 22.

If the work piece 6 is only to be heated, the system is controlled as follows.

First, by means of the time adjusting mechanism 16 of the time switch 14 the desired heating period is adjusted. Then, by transient closing of the starting contact S the time switch 14 is operated. The heating is then switched on and automatically switched out by the time switch after the predetermined period has elapsed. Then the high-frequency heated work piece is cooled in the natural way.

If it is desired to apply a forced cooling to the work piece, the starting contact S is not only closed transiently, as in the aforesaid case, but it is kept closed, so that the cooling switching device 18, after a period determined by a delay device 23, is excited automatically through a conductor 24.

The delay device 23, as well as the time switch 14, is connected through the conductor 15 to the connecting terminals of the starting contact S. The delay device 23 is preferably adjustable and may, for example, be constituted by a relay of known type, responding with time lag, for example a thermal relay or a switching clock-work. As an alternative, use may be made of an electronic delay device, for example, a suitable trigger circuit (one-short multivibrator).

Since, in principle, in the system shown in Fig. 1 the heating period and the delay before switching on the cooling fluid are independent of one another, it is possible to cool forcedly the work piece during the last part of the heating period. This may be desired, for example for tempering.

If a forced cooling is only desired immediately after the heating operation, the control-apparatus 14, 23, 18 may be simplified by using the time switch 14 at the same time as a delay device. The time switch 14 is connected, in this case, through the conductor 25 (shown in broken lines in Fig. 1) to the cooling switching device 18 and the delay device 23 is dispensed with.

Figs. 2 and 3 are detailed embodiments of apparatus which are very suitable in practice.

Fig. 2 is a timing circuit of known type, constructed as a multivibrator with a single stable operational position. It contains a combination tube 26 with two triodes 27, 28, the cathodes of which are connected to ground via a common cathode resistor 29. The anode of the triode 27 is connected to anode voltage lead 31, connected to the terminal 30 of an anode voltage source (not

shown), via the energizing winding of a time-switch relay B and a working contact a_2 of a switching relay A to be described hereinafter, this relay switching on, upon excitation, the high-frequency heating for the work piece via a contact (not shown). The time-switch relay B keeps a holding circuit of the switching relay A closed by means of a working contact b_2 for the duration of the energization.

The control-grid of the triode 27 is connected, for direct-current feed-back, to a tapping point of a potentiometer with resistors 32, 33 and 34 connected between the anode of triode 28 and ground. The anode of triode 28 is connected via an anode resistor 35 to the anode voltage lead 31. Between the anode voltage lead 31 and ground provision is made of a potentiometer having resistors 36 and 37. The control-grid of triode 28 is connected on the one hand via an adjustable resistor 39 to the junction 38 of the potentiometer resistors 36, 37 and on the other hand via a capacitor 40 to a variable tapping point of the cathode resistor 29. The capacitor 40 is shunted by a rest contact b_1 of the time-switching relay B in series with a resistor 41.

With a suitable choice of the control-grid voltage applied to the control-grids of triodes 27 and 28 the triode 27 is cut off in the rest position of the multivibrator described above and the triode 28 draws current. When, upon the energization of the switching relay A, the working contact a_2 is closed, the anode of triode 27 starts to take current, so that, as is known, a relaxation is produced and the multivibrator changes over into the so-called operational position, in which the triode 27 takes the full anode current and the triode 28 is cut off by negative grid bias voltage.

When the triode 27 is conductive, the time-switching relay B included in the anode circuit thereof is energized and the rest contact b_1 is open. The capacitor 40 included in the control-grid circuit of triode 28 is then no longer shunted by the resistor 41, so that the triode 28 can become conductive only with a time lag determined by the charging time constant of the capacitor 40. The charging time constant of the capacitor 40 can be controlled coarsely to adjust the desired heating period by means of the variable resistor 39 and finally by the adjustment of the tapping point on the cathode resistor 29. At the termination of the adjusted time, the triode 28 starts taking current, the multivibrator flops back into the rest position, the time-switching relay B is deenergized and the rest contact b^1 is closed.

In order to render the rest position of the triode 27 independent of temperature fluctuations, the resistor 32 of the potentiometers 32, 33, 34 is shunted by a resistor 42 with negative temperature coefficient.

Fig. 3 is a relay circuit arrangement for use in conjunction with the time switch shown in Fig. 2, this arrangement being connected to terminals 43 and 44 of an alternating-current source for energization of relays. This relay arrangement includes the starting contact S, described with reference to Fig. 1, a switching relay A (referred to above) with working contacts a_1 and a_2 , working contacts b_2 , b_3 and rest contact b_4 of the time-switching relay B of Fig. 2, an auxiliary relay C with a change-over contact c_1 and a working contact c_2 and finally a cooling relay D, which forms part of the cooling switching device 18 of Fig. 1 and which, upon energization, opens a valve (not shown in the figures) to release the cooling fluid.

In the rest position none of the relays A to D is energized and the relay contacts shown in Figs. 2 and 3 occupy the positions shown.

The relay arrangement becomes operative by depressing and hence closing the starting contact S. The starting contact S completes the conventional energizing circuit of switching relay A via the change-over contact c_1 . When the switching relay A is energized, the working contacts a_1 and a_2 are closed and the high-frequency heating

current is switched on by means of a working contact (not shown).

The closure of the working contact a_1 prepares a holding circuit for the switching relay A, this holding circuit including a working contact b_2 of the time-switching relay B.

By closing the working contact a_2 , included in the anode circuit of the triode 27 of the time-switch shown in Fig. 2, the time-switching relay B is energized in the manner described above for a predetermined period. Thus the contacts b_1 , b_2 , b_3 are changed over.

The working contact b_2 completes the holding circuit of the switching relay A, already prepared by the working contact a_1 , so that upon release and thus opening of the starting contact S, or after the change-over contact c_1 has been changed over into the working position, the switching relay A remains energized via an interruptor 45 (to be described hereinafter) and the working contacts a_1 and b_2 .

The working contacts b_3 completes the energizing circuit of the auxiliary relay C via the push button 45 and the working contact a_1 , so that auxiliary relay C is energized, the change-over contact c_1 is moved into the working position and the working contact c_2 is closed.

The change-over of the contact c_1 into the working position results in the completion of a holding circuit for the auxiliary relay C. This holding circuit extends from the terminal 43, via the starting contact S, the change-over contact c_1 in the operational position, and the energizing winding of the auxiliary relay C to the terminal 44. The working contact c_2 results in the preparation of the energization of the cooling relay D.

The closure of the starting contact S thus results, as is described, in the energization of the relays A, B and C in a rapid order of succession. The cooling relay D is not yet energized.

If the starting contact S is closed only transiently i.e. for a time shorter than the duration determined by the time switch, the time switch is operated by means of the switching relay A and the relays B and C are energized. When the time-switching relay B is deenergized, all relay contacts return into the positions shown, since the working contacts b_2 and b_3 open the holding circuit of the switching relay A and the normal energizing circuit of the auxiliary relay C respectively. Thus, upon a transient closure of the starting contact S the work piece to be treated is only heated, since the cooling relay D is not energized.

However, if, subsequent to its closure, the starting contact S is kept closed, the deenergization of the time-switching relay B results it is true, again in the deenergization of the switching relay A, but the auxiliary relay C remains energized via its holding circuit including the starting contact S and the change-over contact c_1 in the working position. The working contact c_2 in the energizing circuit of the cooling relay D remains closed. When, upon deenergization of the time-switching relay B, the rest contact b_4 returns into the rest position (termination of the heating of the work piece), the energizing circuit of the cooling relay D is closed. Relay D is thus energized, so that the water current flows until the starting contact is released.

Thus, when the starting contact S is kept closed, the work piece is heated and immediately thereupon a forced cooling of the work piece is automatically obtained.

The system described above may be constructed for manual operation in a simple manner. In such a case the time switch is not operated. To this end, the system is provided with an auxiliary switch, which, upon being changed over from the time-switch position T into the manual position H, interrupts the anode voltage lead of the time switch via a contact 46 in Fig. 2 and shunts the working contact b_2 in the holding circuit of switching relay A by means of a contact 46' in Fig. 3.

By a transient closure of starting contact S the switching

relay A is energized and remains energized via its holding circuit. The high-frequency heating is then switched on by means of the working contact (not shown and referred to above) of switching relay A. In order to terminate the heating, the holding circuit of the switching relay A includes the interruptor 45.

While the invention has been described by means of a specific example and in a specific embodiment, we do not wish to be limited thereto, for obvious modifications will occur to those skilled in the art without departing from the spirit and scope of the invention.

What is claimed is:

1. High frequency heating apparatus for heating a work piece, comprising switching means for applying heating energy to said work piece for a predetermined period of time, cooling means for applying a cooling medium to said work piece, means for starting the operation of said switching means and said cooling means, and means comprising said switching means for delaying the operation of said cooling means for a predetermined period of time after the actuation of said starting means upon continuous actuation of said starting means, and for preventing the operation of said cooling means upon actuation of said starting means for an interval less than said last-mentioned period of time.

2. High frequency heating apparatus for heating a work piece, comprising switching means for applying heating energy to said work piece for a predetermined period of time, said switching means comprising a time switching relay having a working contact and a rest contact and

5
10
15
